UNITED STATES PATENT OFFICE.

CLAUDE ROY, OF PARIS, FRANCE.

RENDERING WOOD IMPERMEABLE AND RECOVERING LIQUIDS CONTAINED THEREIN.

1,356,015.

Specification of Letters Patent.

Patented Oct. 19, 1920.

Application filed May 28, 1919. Serial No. 300,302.

To all whom it may concern:

Be it known that I, CLAUDE ROY, a citizen of the French Republic, and a resident of Paris, in the Republic of France, have 5 invented Improvements Relating to Rendering Wood Impermeable and Recovering Liquids Contained Therein, which invention is fully set forth in the following specification.

10 My invention relates to apparatus for rendering impermeable newly felled timber in logs and removing from such timber the 15 therein contained sap, in order to avoid subsequent warping of the wood cut from the timber and to permit its being glued. My invention therefore has for its object to enable the timber to be utilized immediately for general industrial purposes and, particularly, for the manufacture of propellers. 20 The apparatus in accordance with my invention permits, moreover, the recovery of the liquid products contained in the timber with a view to the ultimate utilization thereof. 25 By means of my apparatus a liquid solution is injected into the timber which penetrates into all the channels thereof previously washed by an injection of water.

To obtain good results, a liquid solution 30 of casein is injected which solution is prepared by diluting the casein in water to which is added a certain amount of ammonia and quick lime in suitable proportion, in order that the injection can be effected. 35

When the injection of casein is finished, the timber is divided into planks and subjected to drying in a hot chamber, at high temperature, which completes the impermeabilizing by precipitating the solution of casein.

For casein can be substituted any substance having properties and being of a composition similar to casein, in particular 45 all products containing albumin or albuminoids, such as a solution of pure albumin, clarified ox blood, solutions of vegetable or animal albumins, injected by pressure.

Finally, the injection can be effected by 50 suction, *i. e.*, by subjecting the timber to be treated to the action of a vacuum; in this case, the substances contained in the timber are first extracted therefrom then, following, the substance to be injected is introduced.

55 Instead of using either a pressure apparatus or a vacuum apparatus, one can com-

bine the action of the two in applying one apparatus at one end of the log and the other apparatus at the other end of the log.

The timber treated as indicated above is 60 perfectly impermeable and becomes refractory to the action of heat, moisture and light; it does not warp and it glues easily, especially if for this operation glues having a casein base are employed. 65

Moreover, the casein or the solutions can be mixed with a coloring substance of any kind for the purpose of imparting any desired tints. By injecting the liquid in an irregular manner and intermittently, veins 70 more or less dark are formed.

One form of apparatus for carrying out the objects of my invention is shown, by way of example, in the annexed drawing in which— 75

Figure 1 is an end elevation of part of the apparatus.

Fig. 2 is a side elevation partly in section of the same part.

Fig. 3 is a partial longitudinal section 80 thereof.

Fig. 4 is an elevation showing the arrangement for clamping logs separately.

Fig. 5 is a plan, and

Fig. 6 a sectional end elevation thereof. 85

Fig. 7 shows the clamping arrangement applied to a log.

Fig. 8 is a half end elevation of an apparatus showing a modification of the tight joint and the clamping means suitable for 90 logs of medium diameter.

Fig. 9 is a longitudinal section thereof.

Fig. 10 shows in side elevation, on a smaller scale, an arrangement for securing logs of large diameter on the apparatus. 95

Fig. 11 shows another modification of the device for securing a log and the joint-forming head, for logs of great length and small diameter.

As shown in Figs. 1 to 7, the apparatus 100 comprises a support *a*, on which is fixed a base *b* carrying a spindle *c*, on which by a lug *d* is pivoted a cylinder *e*, ending in a flange *e*¹ having ears *e*².

The flange *e*¹ is recessed to provide a circular chamber in which fits the end of a cylindrical body *f*, having chocks *f*¹ in which are pivoted threaded bolts *g*, adapted to engage in the ears *e*² on the flange *e*¹ and carrying nuts. 105

These bolts *g*, the nuts of which bear against the ears *e*², hold the cylinder *e* and 110

the body f rigidly together. A packing ring e^3 insures the liquid tightness of the connections.

The cylindrical body f has a recessed flange f^2 for the reception of a ring h , of which the internal diameter varies according to the thickness of the log, spikes h^1 being also provided for entering the end of the log i .

10 A packing ring j , interposed between the ring h and the end of the log i insures the tightness of the joint between these two.

The log is clamped by means of a contrivance k pivotally connected and inter-pivoted by small links composed of links l ; each of these links k has two cheek plates k^1 presenting a series of teeth intended to enter the log for the purpose of preventing it from turning.

20 The clamp is tightened around the log by coupling screws m , the stems m^1, m^2 of which are pivoted in lugs n carried by the end links k . Threaded bolts o provided with nuts (Fig.

25 2) connect the clamping contrivance with the flange f^2 of the cylindrical body f .

The end of the cylinder e carries two bosses p, r , to which are secured two inlet pipes s, t , one of which s is connected directly to a pump (not shown) when a single 30 element is secured on the support a , and of which the other t is connected to a manifold pipe u mounted on the support a when the apparatus comprises several elements placed in series.

35 In the arrangement shown in Figs. 8 and 9 applicable particularly to logs of medium diameter, the internal recess of the flange f^2 of the cylindrical body f serves to receive a head or ring h for forming a tight joint between the log and the apparatus.

40 For this purpose, the head h has a circular cutting edge h^2 which enters the log i and it provides a seating h^3 also circular, which is provided for receiving a washer h^4 45 of rubber or other suitable material, in close contact with the end of the log i .

The annular portion of the log i comprised between the external periphery of the log and the internal periphery of the joint 50 or washer h^4 , constitutes the necessary jacket for resisting and compensating the pressures set up by the liquids or compressed air, cold or hot, when injected into the log for the purpose of driving out the excess of liquid 55 or of drying the log or, finally, of introducing under pressure a suitable gas for decomposing the organic substances. This jacket prevents, moreover, the expulsion or the leakage of the liquids or of the air through 60 the external periphery of the log, this latter being in the open air.

The arrangement for clamping the log on the apparatus according to Figs. 8 and 9 comprises an annular disk 1, in which slide

65 stems 2 carrying gripping shoes 3 mounted on the ends of clamping screws 4 passing through a flange of the disk 1, these screws serving to press the shoes 3 against the log causing the grippers thereof to enter the log.

70 The annular disk 1 and the log which it supports are connected to the cylindrical body f by threaded bolts 5, the nuts 6 of which bear against the flange f^2 of the cylindrical body f .

75 Logs of large diameter are secured on the apparatus by the arrangement shown in Fig. 10, which comprises the threaded bolts 7 passing through the flange f^2 and having hooks 8 in which are engaged the ends of screw-threaded rods 9, engaged, at the other end, in tightening screws 10.

80 The rods 9 are extended by other rods 11, likewise screw-threaded, which at one end are engaged in the tightening screws 10 while their opposite ends carry claws 12 provided with spikes.

85 These claws are screwed on the rods 11 until they come into contact with the end of the log i and the whole is secured by turning the tightening screws 10 in a manner to exert a pull on the rods 9 and 11 and cause the spikes of the claws 12 to enter the log.

90 Where logs of great length and small diameter are concerned, telegraph poles for example, the head h is extended to form a sleeve h^5 (Fig. 11) in which the end of the log i is engaged and the protective jacket in this case is obtained by the rubber packing h^4 located in the interior of the sleeve h^5 .

95 For such logs, the securing arrangement comprises, as in the preceding case, threaded bolts 7 which pass through the flange f^2 of the cylindrical body f and are formed with hooks 8.

100 Cables or rods 13 are attached to the hooks 8 and also to hooks 14 carried by a collar 15, secured on the log i if desired, at 5 or 6 meters from the apparatus, by clamping screws 16.

105 The collar 15, on the other side opposite to the hooks 14, carries hooks 17 in which are hooked screw-threaded rods 18 engaged in tightening screws 19 and extended by rods 20, also screw-threaded and carrying claws 21 provided with spikes which enter the end of the log i , when the tightening screws 19 are turned to fasten the log.

110 It will be understood from the foregoing, that the various members of the apparatus and also the log which they hold, are interconnected in a joint forming manner. It is therefore sufficient for extracting the sap to supply, by means of a pump, water at a suitable temperature to the pipe s or the manifold pipe u .

115 This water, passing through the cylinder e penetrates into the log, from which it

drives the sap and liquid products which the log contains; these products are collected in a vat for subsequent utilization.

When the water begins to issue pure, the 5 operation is finished and the log is ready to receive the injection to render it impermeable.

This second injection is effected in the 10 same manner and with the same apparatus by which the removal of the sap has been effected, suitable substances or products being employed for that purpose.

When the injection is finished, the log is 15 cut into planks, which are made further impermeable by being dried in a hot chamber.

The apparatus above described enables the 20 injection first into the heart of the log, with the subsequent diffusion of the liquid, gas or hot air by the medullary and concentric channels into all portions of the log, as distinguished from arrangements heretofore employed, such as autoclaves, cast or other iron jackets, etc., by means of which only the 25 albumen crown can be treated by removal of sap, injection and drying, such being only an insignificant portion of the log.

Moreover, with my apparatus, the treatment 30 can be effected as desired either at the foot or head of the tree, and my apparatus can be employed for the injection of all kinds of liquids for preserving, coloring, fireproofing, etc., wood.

What I claim is:

1. In an apparatus for making logs impermeable, the combination with a support 35 and a cylinder adapted to be secured to the end of the log, of a clamping member composed of serrated links pivoted together and adapted to grip the log to be treated, 40 and tightening screws for drawing the links firmly around the log.

2. An apparatus for making logs impermeable comprising a support, a cylinder

adapted to be secured to the end of the log, a means for holding the said cylinder in operative position, said means comprising a clamping member adapted to firmly embrace the end of the log, bolts for connecting said clamping member and said cylinder, an intermediate piece having a recess and adapted 45 to be secured to the said clamping member, a ring located in the recess of the said intermediate piece and provided with a circular cutting edge adapted to enter the log to be treated, a washer located in a circular 50 seat provided in said ring to form an airtight joint, the annular portion of the log inclosed between its external circumference and the internal periphery of the said washer forming a jacket adapted to resist 55 pressure from the inside of the log.

3. In an apparatus as in claim 2 a clamping device comprising an annular member, means for connecting the same to the other parts of the apparatus, stems adapted to 60 slide in said annular member and carrying grippers adapted to engage the log to be treated, and means for forcing said grippers in engagement with the surface of the log.

4. The combination as in claim 3, including bolts formed with hooks, screw-threaded rods adapted to engage in said hooks, nuts having spikes arranged to enter the log upon the rods being tightened, and screws for tightening said rods. 65

5. In an apparatus as specified in claim 1, a plurality of cylinders pivotally mounted on the support, a manifold, two pipes provided on each cylinder, one pipe of each cylinder being connected to said manifold to 70 permit a fluid under pressure to be simultaneously forced through all the cylinders.

In testimony whereof, I have signed this specification.

CLAUDE ROY.
